5-NITRO-2-FURFURAL AZINES

James D. Johnston, Old Saybrook, Conn., assignor to Chas. Pfizer & Co., Inc., New York, N.Y., a corporation of Delaware
No Drawing. Filed June 4, 1963, Ser. No. 285,195
5 Claims. (Cl. 260—240)

This application is a continuation-in-part of Serial No. 803,376, filed April 1, 1959, now U.S. Patent No. 3,099,663, granted July 30, 1963.

This invention is concerned with antimicrobial agents and more particularly with a series of novel azine compounds which exhibit valuable activity against a variety of microorganisms.

I have made the discovery that compounds having the general formula

in which A represents a carbonyl compound from which one carbonyl oxygen has been removed, are remarkably effective antimicrobial agents showing activity against a variety of microorganisms and parasites, among them, organisms which cause disease in animals, including man, and fungi of industrial significance. In this formula A may take a variety of forms, but especially useful compounds are those in which A represents one of a particular group of substituents, as described hereinbelow.

A may, for example, be an alkanone from which the keto oxygen has been abstracted, as represented by the formula

wherein R₁ and R₂ are alkyl groups, usually containing a total of from two to five carbon atoms. Higher alkyl groups may be introduced but ordinarily there will be no advantage. A may thus, for example, be $=C(CH_3)_2$.

Also valuable are those compounds in which A represents cycloalkanone, usually of 5 to 7 carbon atoms, less the keto oxygen, for example

A may likewise be alkanedione from which one keto oxygen has been removed. While a variety of alkanediones may be represented, those containing from 4 to 12 carbon atoms are preferred. A may thus, for example, represent such structures as

In addition, A may advantageously be selected from keto-substituted alcanoic and alkanedioic acids, less the keto oxygen, or from formyl-substituted alcanoic acids, less the carboxaldehyde oxygen. Such substituents will preferably contain a total of up to 12 carbon atoms and will include, for example,

and

where R₁ is hydrogen or alkyl, R₂ is alkyl, and x and y

are zero or integers. In addition, the salts, such as the alkali-metal and amine salts, and esters, wherein the esterifying group is alkyl containing up to about 18 carbon atoms, may be employed in place of the corresponding acids.

Alternatively, A may be derived from an aldehyde by elimination of the carbonyl oxygen. Particularly suitable aldehydes include alkanal and alkenal containing up to 18 carbon atoms, as well as 2-furaldehyde, thiophene-2-carboxaldehyde, monohydroxybenzaldehyde, and benzaldehydes having from one to five alkoxy substituents of from one to three carbon atoms per alkoxy group. In addition, suitable aldehydes also include 1,4-dioxoquinoxaline carboxaldehyde and alkyl-substituted 1,4-dioxoquinoxaline carboxaldehydes in which the alkyl substituent contains from about one to five carbon atoms. They also include γ -cyclohexenylcrotonaldehyde, α -methyl- γ -cyclohexenylcrotonaldehyde, and these crotonaldehydes with alkyl groups of from about one to five carbon atoms as ring substituents.

Among the 1,4-dioxoquinoxaline carboxaldehydes from which the valuable new compounds may be derived are those of the formula

wherein one of said R substituents, preferably in the heterocyclic ring, is formyl. The aromatic ring substituents may be hydrogen, alkyl, chloro, bromo, fluoro, hydroxy, lower alkoxy, carboxy or lower carbalkoxy. Particularly preferred are those wherein one of the R₃ and R₄ substituents is formyl, the other being hydrogen or methyl, and wherein R₅, R₆, R₇ and R₈ are each selected from the group consisting of hydrogen and alkyl containing up to five carbon atoms.

The novel compounds of this invention exhibit in vitro and in vivo activity against a wide variety of microorganisms, including gram positive and gram negative bacteria. Effectiveness is found, for example, against such organisms as *Micrococcus pyogenes* var. *aureus*, including antibiotic-resistant strains, *Streptococcus pyogenes*, *Erysipelothrax rhusiopathiae*, *Corynebacterium diphtheriae*, *Bacillus subtilis*, *Clostridium perfringens*, *Escherichia coli*, *Vibrio comma*, *Pasteurella multocida*, *Mycobacterium 607*, and *Mycobacterium berolinense*. Effectiveness also is exhibited against a variety of other microorganisms, for example, protozoa such as *Endomeba histolytica* and *Trichomonas vaginalis*, and fungi such as *Alternaria solani*, *Cladosporium cladosporoides*, *Trichophyton rubrum*, *Pythium debarynum*, *Aspergillus niger*, and *Penicillium funiculosum*, as well as helminths, including *Syphacia obvelata*.

The compounds of this invention also exhibit activity against various species of *Salmonella*. Among these, a number of compounds are particularly effective in the treatment of *Salmonella* infections in poultry. Each year a significant number of mortalities occur among poultry flocks, especially chickens, as a result of these infections, with a large economic loss resulting. The most important diseases of this nature in poultry result from infections by *Salmonella gallinarum*, which causes fowl typhoid, and *S. pullorum*, which produces white diarrhea in chicks.

Compounds are evaluated for activity against these organisms in the following manner. An experimentally significant number of day-old chicks are artificially in-

fected with the organism by the oral route. One group serves as a control and receives no treatment. This group is fed a nutritionally adequate diet containing sufficient protein, carbohydrate, fat, vitamins and minerals to promote growth in healthy chicks. The other group receives this same basic diet except that the compound under test is admixed with the feed in sufficient quantity to provide a level of 0.1% by weight of active ingredient. The survival time of all chicks is recorded and from this data is calculated the ST_{50} , that is the 50% survival time in days at the 95% confidence limit. The experiment is continued for seven days, at which time the surviving birds are sacrificed and the heart, spleen and liver recovered for quantitative determination of viable *Salmonella* organisms.

Compounds which are found to be particularly effective in this test include, for example, 1-(5-nitro-2-furfural)-2-(dimethyl- β -keto-glutarate) azine, 1-(5-nitro-2-furfural)-2-(ethyl-3-ketobutyrate) azine, 1-(5-nitro-2-furfural)-2-(acetone) azine, 1-ethyl-pyruvate-2-(5-nitro-2-furfural) azine, 1-(5-nitro-2-furfural)-2-(2-carboxaldehyde thiophene) azine, and 1-(5-nitro-2-furfural)-2-(dimethyl 3-keto-2-methyl-glutarate) azine. Especially valuable are 1-(5-nitrofurfurylidene)-2-(3,4-dimethoxy benzylidene) hydrazine, 1-(5-nitrofurfurylidene)-2-(3-methyl-1,4-dioxo-2-quinoxalinylmethylene) hydrazine, 1-(5-nitro-2-furfural)-2-(diethyl- β -ketoglutarate) azine, and 1-(5-nitro-2-furfural)-2-(dimethyl 2,4-dimethyl-3-ketoglutarate) azine.

These new compounds are conveniently prepared by the condensation of 5-nitrofurfural hydrazone with a carbonyl compound, in a solvent such as ethanol or acetonitrile at refluxing temperature, according to the following general reaction

where R_1 and R_2 are selected to conform to the structures hereinabove described. Alternatively, they may be prepared by condensing the hydrazone derived from the carbonyl compound with 5-nitrofurfural, or its diacetate. Some of the carbonyl compounds are readily available, and the others may be synthesized by methods well known to those skilled in the art.

For anti-infective application, these new compounds may be blended with excipients or dispersed in diluents including water, isotonic saline, oils such as sesame oil, and the like. Many modes of administration are possible, including oral, subcutaneous, intramuscular, intravenous and topical application, the choice being dictated by the type and severity of the infection. For administration to poultry in the treatment of *Salmonella* infections, the compounds will ordinarily be administered orally, and may be admixed with feed to provide a concentration of at least about 0.001%, and preferably 0.01% or more by weight of active ingredient.

The following examples are given solely for the purpose of illustration and are not to be construed as limitations of this invention, many variations of which are possible without departing from the spirit or scope thereof.

Example I

A mixture of 0.1 mole 5-nitrofurfural hydrazone and 0.1 mole of dimethyl-2,4-dimethyl-3-keto-glutarate in 500 ml. acetonitrile is heated at refluxing temperatures for about four hours. The resulting solution is filtered and the filtrate treated with activated carbon and evaporated in vacuum. The clear gum is treated with 250 ml. methanol and refrigerated. Filtration of the resulting crystal-

line slurry and recrystallization from methanol yields 1-(5-nitro-2-furfural)-2-(dimethyl-2,4-dimethyl-3-ketoglutarate) azine in the form of a crystalline solid melting at about 155°C.

Example II

Following the procedure of Example I, diethyl acetone-dicarboxylate is caused to react with 5-nitrofurfural hydrazone, yielding 14.6 g. of 1-(5-nitro-2-furfural)-2-(diethyl- β -ketoglutarate) azine in the form of orange plates melting at about 126°C. and having the following elemental analysis: carbon, 49.42%; hydrogen, 5.04%; nitrogen, 12.14%. Ultraviolet absorption maxima are observed at 3100 Å. ($\epsilon=15,100$) and 4060 Å. ($\epsilon=29,250$ in methanol). An infrared absorption maximum is observed at 5.755 microns.

Example III

Following the procedure of Example I, the following series of compounds is prepared:

R ₁	R ₂	R ₃	R ₄
CH ₃	H	CH ₃	CH ₃
H	H	CH ₃	CH ₃
H	H	C ₅ H ₇	C ₅ H ₇
H	H	C ₅ H ₁₁	C ₅ H ₁₁
H	H	C ₅ H ₁₃	C ₅ H ₁₃
H	H	C ₅ H ₁₇	C ₈ H ₁₇
H	H	C ₁₂ H ₂₅	C ₁₂ H ₂₅
H	H	C ₁₈ H ₃₇	C ₁₈ H ₃₇
C ₄ H ₇	C ₃ H ₇	CH ₃	H
CH ₃	CH ₃	C ₅ H ₅	CH ₃
CH ₃	CH ₃	Na	H
CH ₃	CH ₃	NH ₃ (C ₂ H ₅)	NH ₃ (C ₂ H ₅)

Example IV

According to the general procedure of Example I the following additional compounds are prepared from the corresponding carbonyl compounds and 5-nitrofurfural hydrazone:

where A represents one of the following carbonyl compounds with one carboxyl oxygen removed:

acetone	
methyl isobutyl ketone	
ethyl propyl ketone	
cyclopentanone	
cyclohexanone	
cycloheptanone	
2,3-butanedione	
2,4-pentanedione	
4,9-dodecanedione	
2-furaldehyde	
thiophene-2-carboxaldehyde	
salicylaldehyde	
m-hydroxybenzaldehyde	
p-hydroxybenzaldehyde	
o-methoxybenzaldehyde	
p-ethoxybenzaldehyde	
3,4-dimethoxybenzaldehyde	
2,4,6-tripropoxybenzaldehyde	
2,3,4,5,6-pentamethoxybenzaldehyde	
1,4-dioxoquinoxaline-5-carboxaldehyde	
1,4-dioxoquinoxaline-6-carboxaldehyde	
2-methyl-3-amyl-1,4-dioxoquinoxaline-5-carboxaldehyde	
γ -cyclohex-1-ene crotonaldehyde	
γ -(2-methylcyclohex-3-ene) crotonaldehyde	
γ -(6,6-dimethyl-2-methylcyclohex-1-ene) crotonaldehyde	
α -methyl- γ -cyclohex-2-ene crotonaldehyde	
α -methyl- γ -(3-amylocyclohex-4-ene) crotonaldehyde	

α -methyl- γ -(6,6-dimethyl-2-methylcyclohex-1-ene)	
crotonaldehyde	
glyoxylic acid	
ethyl 6-formyl hexanoate	
methyl 10-formyl decanoate	
ethyl pyruvate	
ethyl β -ketobutyrate	
butyl γ -ketovalerate	
11-keto-dodecanoic acid	
8-keto-dodecanoic acid	
diethyl- α -ketomalonate	
4-keto-heptane-1,7-dioic acid	
6-keto-undecane-1,11-dioic acid	
formaldehyde	
acetaldehyde	
isobutyraldehyde	
stearic aldehyde	
crotonaldehyde	

Example V

The product of Example I is subjected to standard in vitro plate tests against a variety of microorganisms. The medium employed is prepared by adding 37 grams of dehydrated Bacto brain-heart infusion B37 (purchased from Difco Laboratories of Detroit) to a liter of distilled water and sterilizing the resulting solution in an autoclave. The compound under test is added to the brain-heart broth in various concentrations, up to 200 mcg. per ml., and the solutions are applied to agar plates seeded with one of the organisms. In this manner the minimum concentration of active ingredient necessary to inhibit organism growth for 24 hours at 37° C. is determined. Results are as follows:

Minimum inhibitory concentration, mcg./ml.	
<i>Bacillus subtilis</i>	25
<i>Clostridium perfringens</i>	25
<i>Bacterium ammoniagenes</i>	200
<i>Aerobacter aerogenes</i>	200
<i>Proteus vulgaris</i>	100
<i>Pseudomonas aeruginosa</i>	100
<i>Erwinia amylovora</i>	100
<i>Desulfovibrio desulfuricans</i>	200
<i>Vibrio comma</i>	100

When 5-nitrofurfural hydrazone is subjected to the same series of tests, it does not inhibit organism growth.

Example VI

The products of Examples II, III and IV are subjected to similar screening tests and are found to be active against a wide variety of Gram-positive and Gram-negative organisms.

Example VII

The product of Example I is screened against *Salmonella* according to the same procedures, with the following results:

Minimum inhibitory concentration, mcg./ml.	
<i>S. typhosa</i>	100
<i>S. pullorum</i>	25
<i>S. gallinarum</i>	50

Example VIII

A typical poultry feed is prepared having the following compositions:

	Percent
Ground yellow corn	51.28
Soybean oil meal (51%)	38.15
Corn oil	6.10
Calcium carbonate	1.20
Dicalcium phosphate	1.35
Salt	0.61
Delmix (commercially available mineral mix containing CaCO_3 and small amounts of iron, zinc, manganese and other salts—Limestone Products Corporation of America, New Jersey)	0.175

5	Vitamin A (5305 IU/lb.)	0.1
	Vitamin D ₃ (681 ICU/lb.)	0.05
	Klotogen F (commercially available form of vitamin K-Abbott Laboratories)	0.0003
5	Pyridoxine hydrochloride	0.0006
	D,L-methionine	0.140
	Niacin U.S.P.	0.0025
	Choline chloride (25%)	0.2
	Riboflavin	0.06
10	Calcium pantothenate (45%)	0.002
	Myvamix (commercially available form of vitamin E)	0.05

The products of Examples I and II are added to different samples of this feed to provide compositions containing 0.1% by weight of active ingredient. These compositions are successfully employed in the treatment of chicks infected with *S. gallinarum*, no toxic effects of the azine being observed. At the conclusion of the experiment the birds are sacrificed and the heart, spleen and liver found to be free of viable *Salmonella*.

When 5-nitrofurfural hydrazone is employed in the same test, it is found to be toxic, causing weight loss and early death. At levels below 0.1%, it is inactive.

25

When 5-nitrofurfural hydrazone is tested in vivo against *S. gallinarum* and *S. pullorum* according to the procedure described in Example VIII at levels of 0.1, 0.05 and 0.01%. Significant activity against both infections is noted at all levels with no toxic effects.

30

Example IX

1 - (5 - nitro-2-furfural)-2-(dimethyl- β -keto-glutarate) azine is tested in vivo against *S. gallinarum* and *S. pullorum* according to the procedure described in Example VIII at levels of 0.1, 0.05 and 0.01%. Significant activity against both infections is noted at all levels with no toxic effects.

35

2,3-dimethyl quinoxaline-1,4-dioxide, 20 g. in 250 ml. ethyl acetate is combined with 15 g. selenium dioxide. The reaction mixture is stirred under gentle reflux for 1/2 hours and the ethyl acetate is then evaporated at reduced pressure. Selenium metal is then separated by filtration and the cake washed with methylene chloride.

40

The combined filtrate and washings are then concentrated at reduced pressure to obtain 15.6 g. of 2-methyl-3-aldehydoquinoxaline-1,4-dioxide melting at 177-179°. Recrystallized from ethyl acetatemethylene chloride the purified substance is obtained in the form of prisms melting at 186-187° (dec.). Analysis, calculated for $C_{10}H_8O_3N_2$: carbon 58.8%, hydrogen 3.95%, nitrogen 13.72%; found: carbon 58.77%, hydrogen 3.93%, nitrogen 13.78%.

45

Example X

Following the procedure of the preceding example, the following aldehydo-quinoxaline-1,4-dioxides are prepared from the corresponding methylquinoxaline-1,4-dioxides.

50

R ₃	R ₄	R ₅	R ₆	R ₇	R ₈
Formyl	H	H	H	H	H
Do	H	H	n-Butyl	n-Butyl	H
Do	H	Methyl	Methyl	Methyl	Methyl
Methyl	Formyl	do	H	H	H
Formyl	Methyl	H	Methyl	H	H
Methyl	Formyl	H	do	H	H
Formyl	Methyl	H	do	Methyl	H
Do	H	Methyl	Ethyl	H	H
Do	H	do	H	Methyl	Methyl
Do	H	Propyl	H	H	H
Do	H	i-Propyl	H	H	H
Do	H	n-Amyl	H	H	H
Methyl	Formyl	do	H	H	H

0.1 75 Those compounds which have a methyl substituent in

the heterocyclic ring and which are unsymmetrically substituted in the aromatic ring are obtained as a mixture of the 2-formyl-3-methyl and the 2-methyl-3-formyl substances. These mixtures are separated by chromatography or by fractional crystallization. Suitable chromatographic adsorbents include alumina, silicic acid and Florisil (activated magnesium silicate). The material is applied to the column of adsorbent, developed and eluted in a solvent such as chloroform, benzene, methanol, or in a mixture of these. For fractional crystallization, appropriate solvent systems include ethyl acetate: methylene chloride and acetone:hexane.

Example XII

2-methyl-3-aldehydo-quinoxaline-1,4-dioxide, 5.1 g. (prepared as described hereinabove), is introduced to a warm solution of 3.9 g. 5-nitrofurfural hydrazone in 250 ml. ethanol. The reaction mixture is heated at reflux temperature for 2 hours, with separation of red, crystalline material beginning after about 10 minutes' reflux. The mixture is then refrigerated and 6.08 of red, crystalline 1-(5-nitrofurylidene)-2-(3-methyl-1,4-dioxo-2-quinoxalinalyimethylene) hydrazine recovered by filtration. The product melts at 190-192°. It exhibits in vitro activity against a variety of microorganisms, including bacteria, fungi and protozoa.

Mice infected with the rodent pinworm *Syphacia obvelata* are treated with the product once daily for two days by the oral route, and at the end of the second day the animals are sacrificed and the cecal content examined. The treated animals show a marked reduction in worms as compared with untreated controls, as follows:

Dosage level, mg./kg. body wt.	Percent efficiency
250	87
125	75
62.5	40

Example XIII

Following the procedure of the preceding example, the following compounds are prepared from 5-nitrofurfural hydrazone and the appropriate aldehydo-quinoxaline-1,4-dioxide:

R ₄	R ₅	R ₆	R ₇	R ₈
H	H	H	H	H
H	H	n-Butyl	n-Butyl	H
H	Methyl	Methyl	Methyl	Methyl
Methyl	do	H	H	H
Do.	H	H	H	Methyl
Do.	H	Methyl	H	H
Do.	H	H	Methyl	H
Do.	H	Methyl	do	H
H	Methyl	Ethyl	H	H
H	do	H	Methyl	Methyl
H	Propyl	H	H	H
H	i-Propyl	H	H	H
H	H	n-Amyl	H	H
Methyl	Ethyl	H	H	H
Do.	H	H	H	Ethyl

These products exhibit activity against a variety of microorganisms and helminths.

Example XIV

1-(5-nitrofurylidene)-2-(3,4-dimethoxy benzylidene) hydrazine and 1-(5-nitrofurylidene)-2-(3-methyl-1,4-dioxo-2-quinoxalinalyimethylene) hydrazine are tested in vivo against *S. gallinarum* according to the procedure of

Example VIII and these compounds exhibit activity at the 0.1% level.

Example XV

The following compounds are tested against *S. gallinarum* according to the procedure of Example VIII and are found to exhibit activity:

1-(5-nitro-2-furfural)-2-(thiazolidine-2,4-dione-2-yl) azine

1-(5-nitro-2-furfural)-2-(ethyl-3-ketobutyrate) azine

1-(5-nitro-2-furfural)-2-(acetone) azine

1-ethyl pyruvate-2-(5-nitro-2-furfural) azine

1-(5-nitro-2-furfural)-2-(5-n-butylthiazolid-2,4-dione-2-yl) azine

1-(5-nitro-2-furfural)-2-(2-carboxaldehyde thiophene) azine

1-(5-nitro-2-furfural)-2-(dimethyl 3-keto-2-methyl-glutarate) azine

1-(5-nitro-2-furfural)-2-(5-dodecylthiazolid-2,4-dione-2-yl) azine.

What is claimed is:

1. A compound of the formula

wherein A is a substituted methylidene moiety derived from a carbonyl compound of the formula

wherein one of said R₃ and R₄ substituents is formyl, the other of said R₃ and R₄ substituents is selected from the group consisting of hydrogen and methyl, and said R₅, R₆, R₇ and R₈ substituents are each selected from the group consisting of hydrogen and alkyl containing up to five carbon atoms.

2. A compound of the formula

wherein A is a substituted methylidene moiety derived from a carbonyl compound selected from the group consisting of alkanone containing from 3 to 6 carbon atoms, cycloalkanone containing from 5 to 7 carbon atoms and alkanedione containing from 4 to 12 carbon atoms.

3. A compound of the formula

wherein A is a substituted methylidene moiety derived from a carbonyl compound selected from the group consisting of alkanal containing up to 18 carbon atoms and alkenal containing up to 18 carbon atoms.

4. A compound of the formula

wherein A is a substituted methylidene moiety derived from a carbonyl compound selected from the group consisting of monohydroxybenzaldehyde and alkoxybenzaldehyde containing from 1 to 3 carbon atoms in the alkoxy group.

5. A compound of the formula

wherein A is a substituted methyldene moiety derived from a carbonyl compound selected from the group consisting of γ -cyclohexenylcrotonaldehyde, lower-alkyl-substituted γ -cyclohexenylcrotonaldehyde wherein the alkyl group is a ring substituent, α -methyl- γ -cyclohexenylcrotonaldehyde and lower-alkyl-substituted α -methyl- γ -cyclohexenylcrotonaldehyde wherein the alkyl group is a ring substituent.
